UNITED STATES PATENT OFFICE

164,110

COMBINATION DISPENSER AND CHANGE TRAY

Thomas J. Foley, Chicago, and George W. Emmert, Berwyn, Ill., assignors to The Curtiss Candy Company, Chicago, Ill., a corporation of Illinois

Application April 12, 1949, Serial No. 1,926

Term of patent 14 years

(Cl. D52—3)

To all whom it may concern:

Be it known that we, Thomas J. Foley and George W. Emmert, citizens of the United States of America, and residents, respectively, of Chicago, county of Cook, State of Illinois, and of Berwyn, county of Cook, State of Illinois, have invented a new, original, and ornamental Design for Combination Dispenser and Change Tray, of which the following is a specification, reference being had to the accompanying drawing, forming a part thereof, wherein:

Figure 1 is a perspective view of a combination dispenser and change tray embodying our new design.

Fig. 2 is a front view thereof.

Fig. 3 is a side view thereof.

Fig. 4 is a top view thereof.

The broken lines indicate stacked sticks of chewing gum for illustrative purposes only.

What we claim is:

The ornamental design for a combination dispenser and change tray, substantially as shown and described.

THOMAS J. FOLEY.
GEORGE W. EMMERT.
